UNITED STATES PATENT OFFICE.

SAMUEL T. BOLE, OF PHILADELPHIA, PENNSYLVANIA, ASSIGNOR TO
JOHN A. BRILL, OF PHILADELPHIA, PENNSYLVANIA.

ELECTRIC SPRINKLING-CAR.

No. 830,046.

Specification of Letters Patent.

Patented Sept. 4, 1906.

Application filed May 18, 1905. Serial No. 260,918.

To all whom it may concern:

Be it known that I, SAMUEL T. BOLE, a citizen of the United States, and a resident of the city and county of Philadelphia, State of Pennsylvania, have invented certain new and useful Improvements in Electric Sprinkling-Cars, of which the following is a specification.

The object of my invention is to provide a car of this class which will force water through the nozzles or allow it to flow by gravity and also to provide means for filling the tank when water is supplied without pressure. This object is accomplished by means of my invention, one embodiment 15 of which is herein described.

For a more particular description of my invention, reference is to be had to the accompanying drawings, forming a part hereof, in which—

20 Figure 1 is a view showing a tank and pump and pipe connections between them, as well as portions of the car structure, Fig. 2 is a similar view showing the valves opened and closed for a different connection, 25 unnecessary parts being omitted. Figs. 3 and 4 are sectional views showing the relief-valve, Fig. 4 being taken on the line 4-4 of Fig. 3 looking in the direction of the arrows. Fig. 5 is a plan view of the parts shown in Fig. 1, the tank being omitted. Fig. 6 is a side elevation of the parts shown in Fig. 5.

Throughout the various views of the drawings, similar reference characters designate similar parts.

35 The tank 1 is supported on any suitable car-frame 2 in the customary manner, as by the bolsters 3, resting on the floor 4. This tank 1 is connected to a vertical pipe 5, which is connected to a horizontal pipe 6 with 40 a valve 7, both located above the floor 4, and a second horizontally-disposed pipe 8, connected at one end to a centrifugal pump 9 and at its other to a vertical pipe 10, that is connected with the nozzle supply-pipe 11, 45 which is preferably placed above the floor-level. The nozzle supply-pipe 11 is connected by a T 12 to the cross-pipe 13, which is united by elbows 14 to the longitudinally-extending nozzle-pipes 15. The nozzles at 50 the ends of these pipes may be of any suitable form.

The pipe 5 is provided with a relief-valve

16, which is conveniently located between the pipes 6 and 8. This relief-valve is shown somewhat in detail in Figs. 3 and 4. The 55 casing 17 is preferably given the shape indicated and is provided with a spindle 18 near its lower end. This spindle 18 is journaled in the casing 17 and has its outer end protrude through a stuffing-box 19, and a handle 60 20 is fixed to this projecting part. A cam 21 is fixed to this spindle 18 and acts to raise a valve 22 from its seat 23 against the action of a spring 24, which surrounds a rod 25, that is riveted at its upper end to a crossing 26 in 65 the casing 17. The valve 22 is also provided with diametrically opposite and parallel guides 27, which run vertically between fixed guides 28. The movement of this valve 22 is limited in a vertical direction by 70 the rod 25 and seat 23. The casing 17 is sufficiently enlarged at 29 to permit the water to flow freely by the valve 22 when it is raised from its seat either by the cam 21 or the pressure of the water under the valve 22, 75 which may be sufficient to overcome the resistance offered by the spring 24, as will more fully appear below.

The outflow-opening of the pump 9 is connected with the pipe 8 in any suitable manner. The inflow-opening is connected similarly to a pipe 30, which is united to a T 31, which is fixed to a valve 32 and horizontal pipe 33, which is adapted to be connected with any suitable source of water-supply. 85 The third opening of the T 31 is connected by a vertical pipe 34 and elbow 35 to the short pipe 35^a to the valve 7.

The pump 9 is connected by a shaft 36 to a motor 37. The pump 9 and motor 37 may 90 be supported in any suitable way as may be found most convenient. In Fig. 6 they are shown under the car-body. The precise form of support from the car-bdy is not shown, as it is obvious that any well-known sort of suspended platform may be employed.

From the foregoing the operation of my improved sprinkler will be readily understood. In Fig. 1 the arrows indicate the direction taken by the water when forced into 100 the tank 1. This water enters through the pipe 33, valve 32, T 31, pipe 30, pump 9, pipe 8, through the valve 16, which is opened by the cam 21 and pipe 5 into the tank 1, the valve 7

and nozzles being closed. When the tank is filled, the valves 32 and 16 are closed and the valve 7 opened. The water is distributed as shown in Fig. 2. It flows through the pipes 5 and 6, valve 7, pipes 35^a, 34, T 31, pipe 30, pump 9, pipes 8, 10, 11, 13, and 15 to the nozzles. If the nozzles should be suddenly closed, as is absolutely necessary in practice, the relief-valve 16 takes the overflow, the spring 24 permitting the valve 22 to leave its seat. From this it is apparent that it is not necessary to stop the motor at any time while the car is in use, or if the effect of the pump is not desired the motor may be stopped and water allowed to flow through it as a pipe, or both of these methods of use may be alternately employed.

In the foregoing has been described one embodiment of my invention. It is obvious that many others may be employed which utilize its essential characteristics, so that I do not regard it as limited to the precise disclosure herein made, but as broad enough to cover all structures that come within the scope of the annexed claim.

What I claim is—

In a device of the class described, a combination of a tank and induction-pipe leading downwardly therefrom, a spring relief-valve in said pipe, and manually-operated means in said valve for opening the same against the action of said spring, a pump connecting with said pipe and also with a nozzle-pipe and branch pipe leading around said pump from the induction side of the pump to said tank induction-pipe, and a valve in said branch pipe and also means for connecting said branch pipe with a source of water-supply, whereby said pump while continuously running in one direction may be caused to force liquid into said tank, or to withdraw liquid therefrom and supply it to the nozzle-pipe, or to simply circulate the liquid when the nozzles are closed, whereby all undue stresses are removed from the nozzles.

Signed this 15th day of May, 1905.

SAMUEL T. BOLE.
